CLAIM

The ornamental design for an electric vehicle charging [system] device, as shown and described.

DESCRIPTION

FIG. 1 is [an upper left front] a top, front, and left side perspective view of an electric vehicle charging [system showing] device embodying our new design;

FIG. 2 is [an upper right rear] a top, rear, and right side perspective view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof;

FIG. 8 is a bottom plan view thereof;

FIG. 9 is [a top left from] an enlarged and partial top, front, and left side perspective [cutaway] view thereof showing illumination elements;

FIG. 10 is [a side and enlarged elevational cutaway] an enlarged and partial side elevational view [of the electric vehicle charging system of FIGS. 4 and 6] thereof; and,

FIG. 11 is an enlarged bottom plan view thereof showing details of the air vents [of the electric vehicle charging system of FIG. 8].

[The shade lines in the Figures show contour and not surface ornamentation.]

The broken lines in the Figures show portions of the electric vehicle charging **system** *device* which forms no part of the claimed design.
